HAND MIRROR

Filed July 23, 1930

UNITED STATES PATENT OFFICE

FRANK X. CAMPBELL, OF BRONX, NEW YORK, ASSIGNOR TO ALL-VIEW MIRROR CO., INC.,
OF NEW YORK, N. Y., A CORPORATION OF NEW YORK

HAND MIRROR

Application filed July 23, 1930. Serial No. 470,192.

This invention pertains to hand mirrors and has for one of its objects to provide a device of this character which includes a pair of swingable mirrors to a common supporting handle embodying novel means for releasably retaining the mirrors in opened or closed position relative to each other.

A further important object is to provide a mirror of the character above set forth which shall present a neat and attractive appearance in both opened and closed positions and which may be expeditiously moved to either position when desired.

The invention will be more readily understood by reference to the accompanying drawings forming a part of this application and in which:

Figure 1 is a view in elevation showing a mirror constructed in accordance with this invention in closed position,

Figure 2 is a top plan view of the device showing the same in open position,

Figure 3 is a fragmentary sectional view on an enlarged scale through the hinged portions of the mirrors,

Figure 4 is a fragmentary sectional view on an enlarged scale through the free end portion of one of the mirrors,

Figure 5 is a detail view in top plan of one of the locking or retaining elements,

Figure 6 is a view in top plan showing another of the locking elements,

Figure 7 is a fragmentary detail view in perspective showing a corner portion of the mirror supporting frames,

Figure 8 is a detail view in perspective showing a corner portion of one of the mirror securing or retaining frames.

Referring to the drawings in detail it will be seen that the reference numerals 1 and 2 designate a pair of substantially rectangular metallic supporting frames of angle iron cross section having formed integrally on one side alined hinge eyes 3 through which the pivot rod 4 extends in a manner to swingably connect the frames 1 and 2 together. On the inner upper corner portion of the frame 1 is an angular bracket 5 having one leg secured by any suitable means such as riveting on the upper side of the frame 1

and its other leg extending downwardly along the inner side of said frame 1 and socketed for the reception of the upper end portion of the pivot pin 4. An eye 6 is disposed on the angular brackets 5 for hanging the mirror on a suitable support such as a hook.

A handle 7 is fixed on the lower end of the pivot rod 4 and also mounted on said pivot rod between the lowermost hinge eye 3 and the handle 7 is a sleeve 8 with an enlarged lower end portion. A metallic disk 9 is rotatably mounted on the pivot rod 4 for rest on the upper end of the handle 7, said disk 9 having formed integrally thereon an arm 10 provided with perforations for rigidly anchoring same to the lower side of the frame 2 as best seen in Figure 1 of the drawings. The disk 9 is provided with a plurality of radial grooves 11 in its upper face. Another disk of metal 12 is also rotatably disposed on the pivot rod 4 for rest on the lower disk 9 and is provided with an integral arm 13 provided with holes for the passage of securing elements for rigidly securing said arm to the lower side of the frame 1. The disk 12 has formed therein a radial detent 14 adapted to seat in the grooves 11 of disk 9. Encircling the pivot rod 4 intermediate the sleeve 8 and the upper disk 12 is a spring washer 15 which yielding-ly urges the upper disk 12 against the lower disk 9. In this manner relative rotation of the disks 9 and 12 when the detent 14 is seated in any of the grooves 11 and swinging movement of the frames 1 and 2 will be normally prevented.

It will thus be seen that the frames 1 and 2 will be releasably retained in adjusted position. Mounted in each of the frames 1 and 2 is a mirror 16 which rests against a supporting panel 17 and in back of each of the supporting panels is a backing plate or sheet 18 the outer face of which may be suitably ornamented.

The mirrors 16, panels 17 and the backing plates or sheets 18 are secured in their respective frames 1 and 2 through the medium of the substantially rectangular retaining frames 19 of angle iron cross section which

fit in the supporting frames 1 and 2, fastening elements in the form of nails or brads or the like 20 being inserted through registering openings provided therefor in the frames 5 1 and 2 and the retaining frames 19 and anchored in the panels 17 for securing the retaining frames in position, as illustrated to advantage in Figure 4 of the drawing.

A suitable thumb piece 21 is mounted on 10 the free side of the supporting frame 1, to facilitate opening the mirrors.

While, for the purpose of illustration, one form of the invention has been shown and described in considerable detail, it is understood, of course, that the invention is not so limited and that the inventive idea is susceptible of various mechanical expressions within the limits of the appended claims.

Having thus described my invention, what 20 I claim is:

1. A mirror of the character described comprising a pivot rod, a pair of frames mounted for swinging movement on the rod, mirrors mounted in the frames, a lower disk 25 rotatably mounted on the rod having a plurality of radially extending grooves in its upper face, an integral arm projecting from one side of the lower disk and rigidly connected to one of the frames for swinging 30 movement therewith, an upper disk rotatably mounted in the rod adjacent the lower disk, a detent on the lower face of the upper disk engageable selectively in the grooves of the lower disk, an integral arm projecting from 35 one side of the upper disk and rigidly connected to the other frame for swinging movement therewith, and a resilient washer mounted on the rod and engaged with the upper disk in a manner to yieldingly engage 40 said upper disk with the lower disk for releasably retaining the detent in the grooves.

2. A mirror of the character described comprising an elongated pivot rod, a pair of frames mounted for swinging movement on 45 the rod, mirrors mounted in the frames, a handle fixed on the lower end portion of the rod, a sleeve mounted on the rod in spaced relation to the handle, a lower disk rotatably mounted on the rod for rest on the handle 50 and having a plurality of radially extending grooves in its upper face, an integral arm projecting from one side of the lower disk and rigidly connected to one of the frames for swinging movement therewith, an upper 55 disk rotatably mounted on the rod, a detent on the lower side of the upper disk for selective engagement in the grooves of the lower disk, an integral arm projecting from one side of the upper disk and rigidly connected 60 to the other frame for swinging movement therewith, a resilient washer mounted on the rod between the upper disk and the sleeve and engaged with the upper disk in a manner to yieldingly urge same against the lower 65 disk for releasably retaining the detent in

the groove in a manner to releasably secure the disks against relative rotation on the rod.

In testimony whereof I affix my signature.

FRANK X. CAMPBELL.
